TEAR-OPEN ENVELOPE

Daniel D. O'Brien, Waukesha, Wis.

Application April 4, 1935, Serial No. 14,646

1 Claim. (Cl. 229—85)

This invention pertains to envelopes and the like, and has for one of its primary objects the provision of means whereby the envelope can be readily opened after sealing without employance of extraneous implements.

Another salient object of my invention is the provision of an envelope having its sealing flaps so formed that a portion of the side flaps will be exposed, whereby the same can be readily grasped by the thumb and forefinger of the recipient for tearing open the envelope to expose the contents to view without danger of mutilating the contents in any way.

A further important object of my invention is the provision of novel means for forming the side flaps themselves, whereby the same will constitute a means for opening the envelope without danger of the side flaps themselves tearing.

A still further object of my invention is to provide an improved envelope of the above character, which will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawing, in which drawing:

30 Figure 1 is a rear elevation of my improved envelope showing the same in its sealed condition.

Figure 2 is a similar view, showing the sealing flap in its raised position.

35 Figure 3 is an enlarged detail fragmentary view, showing the arrangement of the cuts in the sealing and bottom flaps for exposing the apex of a side flap.

Figure 4 is an enlarged fragmentary longitudinal section through the envelope, taken substantially on the lines 4—4 of Figure 3, looking in the direction of the arrows.

40 Figure 5 is a rear elevation of my improved envelope after the same has been opened at one end, the view being taken on a smaller scale than Figures 1 and 2.

Figure 6 is a plan view of the blank of the envelope, taken on the same scale as Figure 5, and with one side flap folded to form the tearing member.

50 Figure 7 is a view similar to Figure 2, showing a slightly modified form of my invention.

Referring to the drawing in detail, wherein similar reference characters designate corresponding parts throughout the several views, the letter E generally indicates one form of my im-

proved envelope. As shown, the envelope E includes the front imperforate wall 10, having formed integral therewith the bottom flap 11, the top sealing flap 12, and the laterally extending side flaps 13 and 14. The bottom flap 11 and the sealing flap 12 are folded on longitudinal lines in the ordinary manner, and after the folding of the side flaps 13 and 14 on transverse lines, the bottom flap 11 is secured to the side flaps in any desired way, such as by the use of 10 suitable adhesive.

The sealing flap 12 also carries an adhesive 15, whereby the same can be secured in its closed position after the matter to be mailed has been placed in the envelope.

In accordance with my invention the bottom flap 11 and the sealing flap 12 are provided with triangular-shaped cutout portions 16, which are adapted to align or register when the sealing flap is closed. These cutout portions 16 are so disposed as to overlie the points or apex portions of the side flaps 13 and 14, so that said points can be readily grasped by the recipient of the envelope so as to facilitate the opening of the envelope. The points can be easily grasped by 25 simply folding the envelope on a transverse line adjacent to the cutout portions 16, so that the points of the side flaps will project through said cutout portions or openings. It is preferred to have the base portions of the triangular openings or cutout portions 16 of an arcuate shape, so that the corners of the openings will readily tear when the points of the side flaps are pulled, it being noted that the side inclined walls of the openings or cutout portions lie alongside of the 35 side edges of the side flaps.

The side flaps 13 and 14 themselves are formed in a novel manner to facilitate the opening of the envelope, and the formation of the side flaps, constitute one of the important objects of my 40 invention.

By referring to Figures 5 and 6, it will be noted that the side flaps before folding are of a substantial square shape, and that the sides of the flap are folded on diagonal lines 17 and 18, to 45 provide side wings 19. The side wings 19 reinforce the flaps 13 and 14, and the flaps have a folded edge to facilitate the tearing of the bottom flap 11 and the sealing flap 12.

In Figure 7 I have shown a slightly modified form of the invention, and in this form the envelope is generally indicated by the reference character M. The bottom flap 20 of the envelope M, and the sealing flap 21 thereof, are provided 55

with single openings 22 and 23, respectively, which are adapted to aline when the sealing flap is in its lowered position. These openings 22 are disposed substantially at the transverse center of the envelope, and overlie the points of the side flaps 23 and 24 of the envelope. This form M of my envelope is opened in the same manner as the form previously described.

Not only do the cutout portions constitute means for facilitating the opening of the envelope, but the same also prevent the opening of the envelope without detection, for if an attempt is made to steam open the envelope, the sealing flap being weakened by the cutout portions is liable to tear. The tearing of the sealing flap will call attention to the fact that the envelope has been tampered with.

From the foregoing description it can be seen that I have provided an exceptionally simple form of envelope, which can be readily opened

without any difficulty at all on the part of the receiver.

Changes in details may be made without departing from the spirit or the scope of this invention, but what I claim as new is:—

An envelope comprising a front wall, side flaps formed on the ends of the front wall and folded over the rear face thereof, a bottom flap formed on the front wall and folded over the lower face thereof and connected with the side flaps, a sealing flap formed on the front wall adapted to be folded over the rear face thereof and connected with the bottom and side flaps, said bottom and sealing flaps being provided with openings adapted to register when the sealing flap is in its closed position, said openings overlying the inner ends of the side flaps, said side flaps being of a triangular shape and having forwardly folded side wings, as and for the purpose specified.

DANIEL D. O'BRIEN.
